GOLF PRACTICE PUTTING MAT

John Thomas Sarvay, Lakewood, Ohio, assignor to The Standard Products Company, Cleveland, Ohio

Filed Dec. 15, 1969, Ser. No. 20,499

Term of patent 14 years

Int. Cl. D21—01

U.S. Cl. D34—5

FIG. 1 is a perspective view of the golf practice putting mat showing my new design;

FIG. 2 is an end elevation view thereof; and

FIG. 3 is a front elevation view thereof.

The sides and bottom surfaces not shown are plane surfaces.

The surface omitted at the break lines is identical to the adjacent surfaces.

I claim:

The ornamental design of a golf practice putting mat, as shown and described.
